DESIGN FOR A STRIP SHINGLE

John A. Topping, Bronxville, N. Y., assignor to
Asphalt Process Corporation, New York, N. Y.,
a corporation of New Jersey

Application November 14, 1933, Serial No. 49,725

Term of patent 14 years

To all whom it may concern:

Be it known that JOHN A. TOPPING, a citizen of the United States, residing at Bronxville, county of Westchester, State of New York, has invented a new, original, and ornamental Design for a Strip Shingle, of which the following is a specification, reference being had to the accompanying drawing forming part thereof.

The figure is a face view of a strip shingle showing my new design.

It is understood that the design claimed may be embodied in a strip of definite or of indefinite length which may be used as a roof covering or may be embodied in a siding or other building covering or similar article of manufacture without departing from the spirit of my invention.

What I claim is:

The ornamental design for a strip shingle as shown and described.

JOHN A. TOPPING.
